(57) **CLAIM**

The ornamental design for a jewelry article, as shown and described.

DESCRIPTION

FIG. 1 is a perspective view of a jewelry article showing my new design;

FIG. 2 is a top plan view of the jewelry article of FIG. 1; FIG. 3 is a bottom plan view of the jewelry article of FIG. 1;

FIG. 4 is a right side view of the jewelry article of FIG. 1; FIG. 5 is a right side view of the jewelry article of FIG. 1; FIG. 6 is a front view of the jewelry article of FIG. 1; and, FIG. 7 is a rear view of the jewelry article of FIG. 1. The broken lines shown in FIGS. 1-6 illustrate portions of the jewelry article that form no part of the claimed design.

1 Claim, 6 Drawing Sheets
